UNITED STATES PATENT OFFICE.

WILLIAM GEORGE ABBOTT, JR., OF WILTON, NEW HAMPSHIRE, ASSIGNOR TO ATLANTIC TERRA COTTA COMPANY, OF NEW YORK, N. Y., A CORPORATION OF NEW YORK.

CUTTING-MACHINE.

1,252,531.

Specification of Letters Patent. Patented Jan. 8, 1918.

Application filed March 2, 1915. Serial No. 11,589.

To all whom it may concern:

Be it known that I, WILLIAM G. ABBOTT, Jr., citizen of the United States, and resident of Wilton, in the county of Hillsborough and State of New Hampshire, have invented new and useful Improvements in Cutting-Machines, of which the following is a specification.

This invention relates to machines for cutting away or reaming out the surfaces of objects of various kinds, and is particularly designed for "rabbeting," so-called, or cutting out depressions in the faces of plaster models from which are made building blocks or bricks of terra cotta, cement, clay or similar materials, or for "rabbeting" the blocks themselves. In preparing blocks of this character it is customary to dig out or chip out, by hand, a depression or recess in the faces of the models corresponding to the faces of the blocks which are to be juxtaposed in building, and to plane off or level the surfaces surrounding the depressions so that a close and even joint may be secured between adjacent blocks. The depressions in the blocks may be filled with cement or mortar. This method of forming the depressions, whether in the models or in the blocks themselves, is slow, crude and expensive, and it is the principal object of the present invention to provide a machine which will cut said depression quickly, accurately and neatly, without danger of breaking or cracking the work. It will be understood that the blocks are usually made in molds, formed from plaster models, but the invention is equally applicable to recessing or "rabbeting" either the models or the blocks themselves which are made in the molds.

In the accompanying drawings which illustrate one embodiment of the invention,—

Figure 1 is a side elevation of the machine;

Fig. 2 is a front elevation of the machine;

Fig. 3 is an enlarged cross section of the cutter head, on line 3—3 of Fig. 1;

Fig. 4 is a detail view, partly in section and partly in elevation, on line 4—4, of Fig. 3;

Fig. 5 is a face view of the cutting tool;

Fig. 6 is a sectional view of the cutter head on line 6—6 of Fig. 2;

Fig. 7 is a section on line 7—7 of Fig. 3;

Fig. 8 is a section on line 8—8 of Fig. 6; Fig. 9 is a sectional view, partly broken away, on line 9—9 of Fig. 2;

Fig. 10 is a section on line 10—10 of Fig. 9;

Fig. 11 is a section on line 11—11 of Fig. 9; and

Fig. 12 is a perspective view of the finished model or block.

Referring to the drawings, 15 represents the frame of the machine by which the working parts are carried, and 16 is the work table for supporting the block B to be operated upon. The table 16 is provided at its forward end with a flange or stop 17 to engage the block or model in correct position for the cutting operation. As blocks or models of various sizes are to be treated, the table may be provided with removable pegs 18 (Fig. 1) which are inserted in conveniently disposed holes in the table. Wedges 19 are then forced between the block or model B and pegs 18, to clamp the same firmly in position on the table.

The rotary cutting tool C, for cutting or reaming out the depression in the face of the model or block, is carried by a cutter head or carrier, indicated generally at A, and is capable of movement both laterally and vertically, while the cutter is rotating, to cover the area of the depression to be cut, and may also be moved toward and from the model or block so as to be forced into and retracted from the surface of the work. These several movements are provided for by the following structures:

A carriage mounted to move laterally in a direction parallel to the face of the work, comprises a horizontally sliding frame 20 (Figs. 1, 9, 10 and 11) resting on tracks 21 and 22 secured to the machine frame 15. A bracket 23 is secured to the front of the slide 20, and constitutes a part of the sliding frame projecting in front of the table 16. Flanges or lips 24 and 25 are secured to the ends of slide 20, and engage the under sides of tracks 21 and 22 respectively to hold the slide in engagement with the tracks and prevent the racks and pinions which operate the slide from disengaging.

A shaft 26 is journaled on the slide, and carries pinions 27 and 28, keyed to said shaft. Said pinions engage racks 29 and 30 secured respectively to tracks 21 and 22. The rotation of shaft 26 moves the slide laterally

through said racks and pinions. Such rotation is effected by hand wheel 31, journaled on bracket 28, through shaft 32, pinion 33, intermediate gear 34, and gear 35 on said shaft 26.

A pair of upright rods or posts 36 are fixed to bracket 23 of the slide, and constitute the vertical guides on which the cutter head A is mounted. A rack 37 is secured to one of the uprights 36, and is engaged by a pinion, presently to be described, for moving the cutter head up and down on the uprights 36. The sliding frame and upright frame together constitute the laterally movable carriage.

The cutter head A (see especially Figs. 3-8) comprises the frame or housing 38, formed with a pair of cylindrical bearings through which the uprights 36 extend. A short sleeve 39 is mounted to turn in the housing 38, and has keyed thereto a pinion 40, meshing with rack 37, and a worm gear 41. Inside of sleeve 39 is a sleeve 42, pinned to the housing 38, constituting the bearing for sleeve 39, and the journal for the rotary cutter shaft or spindle 43.

The worm gear 41 meshes with a worm 44, fixed to shaft 45, which carries a hand wheel 46. Rotation of hand wheel 46 acts through shaft 45, worm 44, worm gear 41, sleeve 39, pinion 40 and rack 37, to move the cutter head A up and down on uprights 36.

In the forward end of cutter shaft 43 is inserted and fixed a sleeve 47 having a tapered bore to receive the correspondingly tapered stem C' of the cutting tool. The shaft 43 also has a control bore 48 extending completely through it, in which a rod may be inserted to drive the stem of the cutter out of sleeve 47.

The cutter shaft 43 is driven through a pulley 49, keyed to the shaft. A handle 50 on the end of shaft 43 is provided for moving the shaft and cutter endwise toward and away from the model or block B. When the shaft and cutter are pushed forward into operative position, as shown in Figs. 1, 3 and 6, a collar or yoke 51 drops down between the head 52 of the cutter shaft, and the housing 38, and serves as a spacer or lock to hold the cutter shaft and cutter in forward or projected position. The yoke 51 is journaled to swing on stud 53, fixed to the housing 38. When it is desired to retract the cutter from the work the yoke 51 is swung upward to dotted line position (Fig. 4) away from head 52, thus leaving the shaft 43 and the cutter free to be drawn back endwise until the head 52 meets the frame 38. The extent of this movement is sufficient to withdraw the cutter from the depression in the model or block and to clear the face thereof.

The cutter shaft 43 is rotated by the following driving mechanism: Referring to

Figs. 1, 4, 9 and 11,—54 is the main driving shaft, journaled in the frame 15 of the machine. Shaft 54 is rotated by pulley 55 from any convenient source of power. A pulley 56 is mounted on shaft 54 to turn therewith but to slide lengthwise thereof, said pulley and shaft being connected by a feather 57 which works in a groove 58 as in the shaft (Fig. 11). Pulley 56 is moved laterally of the machine with the slide 20 by means of brackets 59, which extend downward from the slide at each side of the pulley 56.

Another pulley shaft 60, mounted on the under side of bracket 23, carries two idler pulleys 61 and 62, arranged side by side; and at the top of the uprights 36 is another idler pulley 63. On the cutter head A below the cutter pulley 49 is pulley 64, journaled on the frame 38.

The belt or cable 65 connects driving pulley 56 with the cutter pulley 49, in all positions of the cutter head A. The course of the cable 65, following its direction of travel indicated by arrows and starting from the top of pulley 56, is as follows: From the top of pulley 56 the cable extends under pulley 62, thence upward and over pulley 63, thence downward and under pulley 64, thence upward and over pulley 49, thence downward and under pulley 61 and thence around pulley 56. It will be observed that a loop is thus formed around pulley 49 affording sufficient frictional engagement to drive the cutting tool, and that as the cutter head A is raised or lowered on the uprights 36, this loop will follow the pulley 49, so that the cable will always be in driving engagement with the cutter pulley 49. As the driving strain of the cable is downward on cutter head A, as well as the weight of the cutter head, I provide a counterweight 66, which is connected with the cutter head A by a cord 67 passing over pulleys 68 and 69 at the top of uprights 36.

The cutting tool C (Figs. 3, 5 and 6) consists of the blade carrier or disk 70, having a beveled or conical periphery, and the blade 71 of U-shaped or bail-like form, secured at its ends to the conical periphery of the disk. The blade is twisted slightly at the middle, thus presenting two salient or advanced cutting edges 73 on opposite edges of the blade and at opposite sides of the center of the tool. The bent over ends 72 are inclined to the axis of the tool so as to bevel the edges of the depression cut by the tool. The leading or cutting edges of the bent over ends 72 of the blade are also a little farther from the center of the tool than the following edges. When the cutter is operated the material cut out from the model or block may pass between the blade and the disk and drop out clear of the cutter.

In operation, the model or block B, in

which the depression is to be cut, is clamped on the work table in the manner already described, the cutting tool being in retracted position, which is permitted by lifting the yoke 51. The tool is brought opposite the point of the model or block where the cutting is to be begun, for example, at one of the lower corners of the area to be cut out, by shifting the sliding carriage laterally, with hand wheel 31, and shifting the cutter head vertically with hand wheel 46. The rotating cutting tool is then forced forward into the face of the model or block by the handle 50. As soon as the tool reaches its forwardmost or operative position the yoke 51 will drop into place, locking the tool in cutting position. The cutter head is then shifted horizontally and vertically by hand wheels 31 and 46, until the entire depression desired in the face of the model or block has been cut or reamed out. In Fig. 2 the depression B' is shown as only partly finished; in Fig. 12 the depression B' is shown as finished.

25 When the cutting has been finished the cutter may be withdrawn again from the depression B' by lifting yoke 51.

It is to be understood that such words as horizontally, vertically, upwardly, downwardly, etc., are herein employed merely in a relative sense more conveniently to refer to relative directions and positions, and that they are not necessarily limited to absolute directions and locations with reference to the earth's surface, although in the preferred embodiment of the invention they are also accurately descriptive of absolute directions and locations.

I claim:

40 1. In a machine of the character described, a stationary work support, a carriage mounted to move in a direction parallel to the surface of the work, a tool carrier mounted to move on said carriage in a direction transverse to the direction of movement of said carriage but parallel to the surface of the work, a rotary cutting tool reciprocatably mounted on said tool carrier, so as to be moved to and from the work, stationary power means, and driving mechanism connecting the power means to the cutting tool so as to rotate the cutting tool in all positions thereof.

2. In a machine of the character described, a stationary work support, a laterally reciprocating frame mounted to move in a direction parallel to the surface of the work, an upright frame mounted on said reciprocating frame, a cutter head mounted to move vertically on said upright frame, a rotary cutting tool journaled in said cutter head, means to shift said cutting tool relatively to the cutter head and to the work, stationary power means, and driving mechanism connecting the power means to the cutting tool

so as to rotate the cutting tool in all positions of the cutter head.

3. In a machine of the character described, a stationary work support, a carriage mounted to move in a direction parallel to the surface of the work, a tool carrier mounted to move on said carriage in a direction transverse to the direction of movement of said carriage but parallel to the surface of the work, a rotary cutting tool mounted on said tool carrier, and driving mechanism operative to rotate said cutting tool in all positions thereof, comprising a cutter pulley on the tool carrier, a driving belt or cable engaging said cutter pulley in all positions of the tool carrier, pulleys mounted on the carriage on opposite sides of the tool carrier substantially in alignment with the path of movement of the tool carrier on the carriage, said belt passing over the latter pulleys so that a portion thereof is disposed along said path of movement in engagement with the cutter pulley in all positions of the tool carrier.

4. In a machine of the character described, a work support, a carriage mounted to move in a direction parallel to the surface of the work, a tool carrier mounted to move on said carriage in a direction transverse to the direction of movement of said carriage but parallel to the surface of the work, a rotary cutting tool mounted on said tool carrier, driving mechanism operative to rotate said cutting tool in all positions thereof comprising a cutter pulley on the tool carrier, a guide pulley on the tool carrier adjacent the cutter pulley, pulleys mounted on the carriage on opposite sides of the tool carrier substantially in alignment with the path of movement of the tool carrier on the carriage, and a belt passing over the latter pulleys so that a portion thereof is disposed along said path of movement in engagement with the cutter and guide pulleys in all positions of the tool carrier, the guide pulley, being so disposed with respect to the cutter pulley as to cause the belt to engage the cutter pulley throughout a relatively large angle.

5. In a machine of the character described, a stationary work support, a laterally reciprocating frame, a pair of uprights fixed to said frame, a cutter head mounted to slide vertically on said uprights, a rotary cutting tool journaled in said cutter head, stationary power means, and driving mechanism connecting the power means to the cutting tool so as to rotate the cutting tool in all positions of the cutter head.

6. In a machine of the character described, a horizontal work support, a movable carriage mounted at least in part at one side of the support so as to be moved along that side, an upright frame extending vertically from the carriage at one side of the work on the support, a cutter head mounted to

slide vertically on said upright frame, a rotary cutting tool journaled in said cutter head, a driving shaft, a driving pulley mounted on said shaft to turn therewith and 5 to slide lengthwise thereof, said pulley being shifted on said shafts with the lateral movement of the carriage, and a belt or cable by which the cutting tool is rotated from the driving pulley.

10 7. In a machine of the character described, a work support, a laterally movable carriage having an upright frame, a cutter head mounted to move vertically on said upright frame, a rotary cutting tool journaled in 15 said cutter head, a driving shaft, a driving pulley mounted on said shaft to turn therewith and to slide lengthwise thereof, said pulley being shifted on said shaft with the lateral movement of the carriage, a pair 20 of idler pulleys at the lower end of said upright frame, an idler pulley at the upper end of said upright frame, a cutter pulley on said cutter head for rotating the cutting tool, and a belt or cable passing around said 25 driving pulley, under both of said lower idler pulleys, over said upper idler pulley, and in driving engagement with said cutter pulley, whereby the cutter pulley travels along the portion of the belt or cable extending 30 between the upper and lower idler pulleys in operative engagement therewith as the cutter head is moved vertically on the upright frame.

8. In a machine of the character described, 35 a cutter head comprising a housing, a fixed sleeve in the housing, a rotatable sleeve surrounding the fixed sleeve, means engaging the rotatable sleeve for transversely moving the head, and a rotary cutter shaft journaled 40 in said fixed sleeve.

9. In a machine of the character described, a cutter head comprising a housing, a fixed sleeve in the housing, a rotatable sleeve surrounding the fixed sleeve and carrying a 45 pinion, a gear meshing with the pinion for transversely moving the head, and a rotary

cutter shaft journaled in said fixed sleeve and movable lengthwise thereof.

10. In a machine of the character described, a cutter head comprising a housing, a fixed sleeve in the housing, a rotatable sleeve surrounding the fixed sleeve, means engaging the rotatable sleeve for transversely moving the head, a rotary cutter shaft journaled in 50 said fixed sleeve and movable lengthwise thereof, and means positively to hold said shaft in its forward or projected position.

11. In a machine of the character described, a cutter head comprising a housing, a fixed sleeve in the housing, a rotatable sleeve surrounding the fixed sleeve, a pinion fixed to the rotatable sleeve adapted to engage a rack, a worm gear fixed to said rotatable sleeve, a worm mounted to turn in the housing and meshing with said worm gear, and a rotary cutter shaft journaled in 55 said fixed sleeve.

12. In a machine of the character described, an upright guide, an upright rack, a cutter head mounted to move vertically on said 70 guide comprising a housing, a fixed sleeve in said housing, a rotatable sleeve surrounding the fixed sleeve, a pinion fixed to the rotatable sleeve meshing with said rack, a worm gear fixed to said rotatable sleeve, a 75 worm mounted to turn in the housing and meshing with said worm gear, and a rotary cutter shaft journaled in said fixed sleeve.

13. In a machine of the character described, a cutter head comprising a housing, a sleeve 80 rotatably mounted therein, a pinion fixed to said sleeve, a rotary cutter shaft journaled within said sleeve having a head at its forward end, and a locking yoke pivoted to said housing adapted to swing in and out 85 between said head and said housing.

Signed by me at Wilton, New Hampshire,
